UNITED STATES PATENT OFFICE.

SAMUEL T. EASTER AND ERNEST E. COOK, OF ABERDEEN, WASHINGTON.

LEAF-SPRING LUBRICATOR.

1,147,930.

Specification of Letters Patent. Patented July 27, 1915.

Application filed April 16, 1915. Serial No. 21,827.

To all whom it may concern:

Be it known that we, SAMUEL T. EASTER and ERNEST E. COOK, citizens of the United States, residing at Aberdeen, in the county 5 of Chehalis and State of Washington, have invented certain new and useful Improvements in Leaf-Spring Lubricators, of which the following is a specification, reference being had to the accompanying drawings.

10 This invention comprehends certain new and useful improvements in means or devices for use in lubricating leaf springs of automobiles or other vehicles, and the invention has for its primary object a simple, 15 durable and efficient construction of device of this character whereby the lubricant may be readily applied to the leaves and diffused between the same, without the necessity of jacking up the vehicle or of separating the 20 leaves to any extent.

A further object of the invention is to provide an improved leaf spring lubricator which is so constructed and arranged that it will not only serve its primary function as 25 a lubricating device, but which will also serve the additional function of holding the leaves in proper alignment with each other, whereby all clips or similar devices may be done away with. And the invention also 30 aims to generally improve and simplify devices of this character so as to render them more useful, convenient and commercially desirable.

With these and other objects in view, as 35 will more fully appear as the description proceeds, the invention consists in certain constructions, arrangements and combinations of the parts that we shall hereinafter describe and claim.

40 For a full understanding of the invention, reference is to be had to the following description and accompanying drawing, in which,

45 Figure 1 is a side elevation of a leaf spring provided with the improvements of our invention. Fig. 2 is an inverted perspective view of a portion of one of the leaves. Fig. 3 is a fragmentary perspective view of one of the leaves looking at the 50 upper face thereof. Fig. 4 is a fragmentary transverse section of two of the leaves, and Fig. 5 is a transverse sectional view of a modified form of the device hereinafter specifically referred to.

55 Corresponding and like parts are referred

to in the following description and designated in all of the views of the accompanying drawing by like reference characters.

Referring to the drawing, the numeral 1 designates the superposed leaves embodying 60 an automobile or similar spring, and 2 designates the usual fastening bolt.

In carrying out our invention, the leaves 1 are provided on either one or both sides with oil receiving devices 3, the same preferably comprising lug-like structures provided with upwardly projecting tubular portions 4 designed to receive the discharge ends of the oil cans or the like, and communicating at their lower ends with ducts 5 in the oil receiving devices, said ducts opening into 70 the lower faces of the leaves and there communicating with transversely extending grooves 7 formed in said faces.

From as much of the description as has preceded in connection with the correlated views of the accompanying drawing, it will be clearly understood that when the oil is applied to the oil receiving devices 3, it will flow down through the ducts 5 and 75 across the grooves 7 and thence be diffused between the adjoining faces of the leaves, whereby the leaves will be effectively lubricated and all squeaking and the like obviated. In the preferred arrangement of the parts, the oil receiving devices 3 are arranged in pairs, one for each leaf with the exception of the lowermost one, the two oil receiving devices of each spring being located respectively on opposite sides of the 80 bolt or fastening device 2, and preferably all of the oil receiving devices are located on the corresponding side edges of the leaves, namely, the outer side edge whereby 85 they will be easily accessible and the operation of oiling the leaves thereby facilitated. But it is to be understood that the invention is not limited in this regard and that various 90 changes may be made in the construction, arrangement and proportions of the parts without departing from the scope of the invention as defined in the appended claims.

For example, if desired, the uppermost leaf alone may be provided with oil receiving devices, as clearly illustrated in Fig. 5, and the other leaves formed with openings 8, whereby the oil which is passed into the oil receiving device or devices of the uppermost leaf, will flow down in between the 105 contacting faces of the subjacent leaves and 110

the entire spring will thereby be lubricated. Various other changes will suggest themselves to the designer, and still be within the scope of the invention.

- 6 It is to be particularly noted that not only does our invention provide means whereby the leaves may be maintained at all times in properly lubricated condition, but, owing to the fact that the oil receiving devices 3 of each leaf extend above the adjoining side edge of the next superjacent leaf, the oil receiving devices will subserve the additional function of holding the leaves in alinement and all clips or similar fastening devices can be done away with. Preferably, the main lug-like body portions of the oil receiving devices directly serve this purpose, as their upper faces extend above the plane of the leaf to which they are attached or of which they form a part, so as to produce shoulders 9 against which the side edge of the leaf above will bear. Preferably the lowermost pair of oil receiving devices 3 extends slightly below the adjoining side edge of the lowermost leaf so as to engage against the side edge of the leaf and prevent disalinement of this lowermost leaf with relation to the superjacent leaves.

30 It is to be understood that wherever the word "oil" is used in the specification and claims, it is intended to be comprehensive enough to cover not only freely flowing oil, but all other substances or ingredients that can be used as a lubricant.

35 What is claimed, is:

1. A spring embodying a plurality of superposed leaves, and oil receiving devices carried by said leaves, the oil receiving devices of the respective leaves engaging the

leaf next above whereby they will hold the 40 leaves in position.

2. A spring embodying a plurality of superposed leaves and oil receiving devices carried by said leaves on the side edges thereof, the oil receiving devices of the respective leaves projecting above and in contact with the side edges of the leaf next above.

3. A spring embodying a plurality of superposed leaves, a bolt connecting said leaves together at the middle thereof, and oil receiving devices carried by the respective leaves on opposite sides of said bolt, said oil receiving devices projecting laterally from the leaves and formed with ducts 55 opening into the lower faces of the leaves, the oil receiving devices being provided with shoulders abutting against the side edge of the next adjacent leaf.

4. A spring embodying a plurality of 60 superposed leaves and oil receiving devices carried by said leaves on the side edges thereof, the oil receiving devices on the leaf next to the lowermost leaf projecting below and in contact with the side edge of 65 the leaf next below all of said oil receiving devices of the respective leaves projecting above and in contact with the side edges of the leaf next above.

In testimony whereof we hereunto affix 70 our signatures in the presence of two witnesses.

SAMUEL T. EASTER.
ERNEST E. COOK.
